UNITED STATES PATENT OFFICE

2,443,139

VISIBLE RESERVOIR HUMIDIFIER FOR
CONTAINERS

Frederick A. Krause, Hinsdale, Ill.

Application July 9, 1943, Serial No. 494,055

3 Claims. (Cl. 299—24)

1

This invention relates to humidifiers and particularly to an inexpensive form of humidifier for use with containers for various kinds of merchandise and materials requiring humidity.

This applicant appreciates that many forms of humidifiers have been made for maintaining humidity conditions in show cases, tobacco containers, etc., and that the art is replete with devices of this character. However, the present invention is directed to a very definite kind of humidifier, namely, a humidifier for opaque containers, such as the common forms of cans and cartons used in the shipment and storage of various kinds of merchandise and materials which require controlled humidity conditions to maintain their strength of quality.

As an example, the shuttlecocks used in the popular game of badminton are made of cork and feathers. These shuttlecocks are merchandised by the dozen in round cartons such as shown in Figs. 1 and 2 herein. These shuttlecocks deteriorate very rapidly when allowed to dry out. In fact, dried out shuttlecocks, even when new, will last only a small fraction of the life of a properly humidified shuttlecock.

Now to maintain such merchandise in proper condition with ordinary humidifying devices during the shipment and while on the shelves of the merchant and even in the hands of the consumer involves widely variable factors of weather, humidity conditions, temperatures and times that are beyond the practical control of the merchants and customers. Under ordinary conditions, people simply will not open up cartons of this character, investigate an interior humidity control device and take the necessary steps to protect the merchandise.

It is the particular object of the present invention to provide a humidifier for opaque containers, having a visual water reservoir element having an adjustable interior humidifier element arranged to keep the merchandise in properly humidified condition as long as water is visible in the reservoir.

Other objects and benefits will be disclosed in the following descriptions and drawings in which—

Fig. 1 is a broken elevation view of a round carton container for shuttlecocks, showing my visual water reservoir and humidifying element;

Fig. 2 is a top plan view of the carton container with humidifier shown in Fig. 1;

Fig. 3 is a cross sectional elevation view of another form of my novel humidifier as applied to a can lid;

2

Fig. 4 is cross sectional elevation view of another form of my humidifier as applied to the top of a container.

Referring to the drawings, and at the outset, particularly to Figs. 1 and 2, I show a special round carton 10 with removable cap members 10a and 10b. This is the carton heretofore referred to in the specifications for packaging shuttlecocks used in the game of badminton. The top of the lid 10a has a round perforation 11 to receive a transparent water reservoir member 12, extending above the lid and resting upon the lid by the flange member 13. The bottom of the reservoir member 12 is closed by a metallic cup member 14 bearing against a rubber washer 15. The cup member 14 is filled with a porous shallow member 16, made of plaster of Paris or similar material selected to provide proper evaporation of moisture from the reservoir 12 into the interior of the carton 10. The plaster of Paris member 16 is held within the cup 14 by a lower washer 17 and is retained in sealed position by the thumb screw member 18 threaded into the boss 19 of the reservoir 12. An opening 14a in the cup 14 is arranged to provide the proper amount of water seepage into the porous evaporator member 16 and the exposed section of the evaporator member 16 below the rim of the cup 14 is adjusted and arranged to provide proper evaporation into the container. The associated reservoir member 12, with its evaporator member 16 is held in the cap 10a by a conventional steel snap ring 20 which locks the assembly in the opening 11 by co-action of the snap ring 20 with the flange 13.

It will be appreciated that by the above construction, I have provided an inexpensive form of humidifier which may be applied to the lid of a carton as illustrated, with the water reservoir plainly visible to indicate the presence of water in the reservoir and proper humidity control for the contents of the carton. It will be appreciated that the structure thus provided does not depend upon great structural strength of the carton but in its unitary form may be effectively retained in cheap cartons, to provide a visible reservoir humidifier for containers of this character.

Now referring to Fig. 3, I show another form of visible reservoir humidifier, the same being applied to a conventional metallic cap for cans. The metallic cap 21 has a central round perforation 21a and over this perforation, I mount a transparent water reservoir member 22. This reservoir is firmly held in position by drawing the flange 23 downward into sealing contact with

the washers 25 and 26 as held between a shoulder of a screwed cup member 24. This cup member is filled with a porous evaporator material, such as plaster of Paris or the like 27 and this porous evaporator member is supplied with water from the reservoir 22 by an opening 240. By changing the size of the opening 240 and the exposure of the porous evaporator member 27, a simple form of visible reservoir humidifier is provided.

Now referring to Fig. 4, I show a special flat form of my humidifier as applied to a can top 28. The top 28 is provided with a central opening 280 on which I mount a special low form of transparent reservoir 29. It will be noted that this reservoir element is below the top of the can and thereby the reservoir is protected by the flange of the can which is advantageous under some conditions. The reservoir element 29 is closed by a steel cup member 30 filled with porous evaporator material 31, held in position by a bottom washer 32, the entire evaporator assembly being sealed by cap screws 34, screwed into bosses 35 to compress the rubber seal ring 33 and thus close the evaporator reservoir. Proper evaporation from this reservoir is provided by holes 300 in the cup member 30 and holes 320 in the washer 32. It will be appreciated that by varying the size of these holes, proper humidity conditions may be adjusted and controlled. The transparent reservoir 29 has a depressed central sealer boss 43 and is closed in a conventional manner by the knurled screw 44 and the washer 45. The entire evaporator assembly is held in the opening 280 by the snap ring 46 and the flange 29a.

In the foregoing description and drawings, I have shown several variations of my visible reservoir humidifier, and it will be appreciated that many other variations are possible. However, I do not wish to be limited in any way by the disclosure except as such limitations are imposed by the following claims.

I now claim as new:

1. A detachable humidifier unit for a container having a rigid cover with an opening therein adapted to receive the humidifier unit, comprising a transparent liquid reservoir, means projecting from the periphery of said reservoir, a cup in open communication with the reservoir, a porous evaporator member in communication with the cup, means for removably attaching the reservoir, the cup and the evaporator member to one another, and a snap ring circumferentially carried by the reservoir positioned to detachably

hold the cover of the container between said peripherally projecting means and the snap ring.

5 2. A detachable humidifier unit for a container having a rigid cover with an opening therein adapted to receive the humidifier unit, comprising a circular transparent liquid reservoir, a flange extending circumferentially around the outer periphery of the reservoir, a cup in open communication with the reservoir, a porous evaporator member in communication with the cup, means for removably attaching the reservoir, the cup and the evaporator member to one another, and a snap ring circumferentially carried by the reservoir positioned to hold the cover of the container between the flange on the reservoir and the snap ring to detachably hold the humidifier unit in the opening in the cover.

10 3. In a humidifier unit adapted to be positioned detachably in an opening in a supporting member the combination of a detachable humidifier unit disposed in the opening in the supporting member, said unit comprising a transparent liquid reservoir, a flange extending circumferentially around the outer periphery of the reservoir, a tubular sleeve carried by the reservoir and extending into the opening in the supporting member and having a groove extending circumferentially thereof adjacent the flange, a cup inserted into the tubular sleeve and being in open communication with the reservoir; means to detachably hold the cup in the sleeve, a porous evaporator member carried within the cup, means to detachably hold the evaporator member in the cup, and a snap ring circumferentially carried 15 30 35 in the groove in the sleeve of the reservoir.

FREDERICK A. KRAUSE.
